FRANKFURTER BUN

Theodore A. Corn, 10000 North Point, San Francisco, Calif. 94109, and Robert M. Harlick, 2330 Wexford, South San Francisco, Calif. 94080

Filed Apr. 14, 1969, Ser. No. 16,743

Term of patent 14 years

Int. Cl. D1—01

U.S. Cl. D1—15

FIG. 1

FIG. 2

FIG. 3

FIG. 4

FIG. 5

FIG. 1 is a side elevational view of a frankfurter bun showing our new design;

FIG. 2 is a top view of the bun shown in FIG. 1;

FIG. 3 is a bottom view of the bun shown in FIG. 1; and

FIG. 4 is a front view of the bun shown in FIG. 1; and

FIG. 5 is a rear view of the bun shown in FIG. 1.

We claim:

The ornamental design for a frankfurter bun, as shown.
